UNITED STATES PATENT OFFICE.

FOSTER DOCKSTADER, OF FAMOSO, CALIFORNIA.

BOILER-CHIPPING DEVICE.

Application filed July 20, 1925. Serial No. 44,790.

This invention relates to boiler chipping devices, and is more particularly directed to a device for removing the incrustations formed upon the interior of boilers by the precipitation from the water employed therein of certain soluble materials which form a hard stone or crusty material upon the inside of the surface of the boiler.

In boilers of light construction, in which water is heated or steam generated, the insoluble salts found in the water or formed therein during the boiling thereof, precipitate out in the form of a film or scale or crust upon the inner surface of the boiler. This incrustation is an effective heat insulating material and makes it difficult for heat to penetrate through the boiler shell to the water. This resistance to heat penetration to the water results in a considerable waste of the heat as the same is directed up the stack and consequently results in a loss of fuel.

When this incrustation is formed upon the inner surface of the shell of the boiler, localized overheating results in many places along the shell of the boiler, particularly those points which are subject to direct convection and radiation of the heat which in many cases has resulted in the burning out of the shell of the boiler and caused considerable damage both to property and human life. The reason for this is that the incrustations prevent the water circulating within the boiler from carrying away the heat from the metal shell and thus the metal becomes intensely heated and, due to the pressure within the boiler, fails. There are certain portions of the interior of the boiler from which the removal of this incrustation is very difficult, for example, that portion of the shell concealed by the small tubes that run lengthwise through most boilers of the fire tube type.

An object of this invention is to provide a device for removing such incrustations more easily and more economically than before, and which is applicable to reach all portions of the boiler.

An object of this invention is to produce a boiler chipping device operated by pneumatic pressure to rapidly oscillate a chipping tool and in which means are provided for preventing or compensating for the rebound of such a chipping tool.

Other objects and advantages of this in-

vention will be apparent from the following detailed description of a preferred embodiment thereof, as illustrated in the accompanying drawings.

In the drawings:

Fig. 1 is a perspective view of a boiler chipping device embodying this invention.

Fig. 2 is an enlarged bottom plan view thereof showing the pneumatic cylinder partly in section and the chipping tool operating rod and casing broken away.

Fig. 3 is an enlarged central side elevation of the boiler chipping device head embodied in this invention.

Fig. 4 is an end elevation taken substantially on the line 4-4 of Fig. 3.

Fig. 5 is a bottom plan view of one form of boiler chipping tool embodied in this invention.

Fig. 6 is a side elevation of a boiler chipping tool illustrated in Fig. 5.

Fig. 7 is a top plan view of another modified form of boiler chipping tool embodied in this invention.

Fig. 8 is a side elevation of a boiler chipping tool shown in Fig. 7.

Fig. 9 is a diagrammatic view of a boiler chipping operation illustrating the boiler chipping device as embodied in this invention in position within a boiler and connected to a source of pneumatic pressure.

In the preferred embodiment of this invention illustrated in the accompanying drawings, 1 illustrates a pneumatic cylinder connected to a flexible conduit 2 which conduit is connected to a source 3 of pneumatic pressure. The pneumatic cylinder 1 embodies a piston 4 having a piston rod 5 and is of common commercial construction and no claim is made to its specific construction or operation.

The piston 4 oscillates rapidly within the pneumatic cylinder 1 under the action of the fluid transmitted through the conduit 2 from the source 3. A heavy steel head 6, in which a special chipping tool 7 is movably held by a pin 8, is rigidly connected to the pneumatic cylinder 1 by means of a heavy tube or pipe 9, as is illustrated at 10 and 11, respectively. The length and curvature of the tube or pipe 9 can be made to suit any vessel into which the entire device is to be inserted. Within the tube 9 is mounted a piston rod 12 which piston rod 12 is the means for transmitting the blows

of the pneumatically operated piston 4 to the chipping tool 7. The end 13 of the piston 12 is engaged by the end of the piston rod 5 and is rapidly reciprocated by the reciprocation of the piston 4 to which the rod 5 is connected. The end 14 of the piston 12 extends through and is reciprocated within the bore 15 of the head 6. The forward end of the piston rod 12 strikes the shoulder 16 of the chipping tool 7 and causes the same to rotate upon the pin 8. The chipping tool 7 is recessed to form the shoulder 16. The chipping tool 7 is provided with a chipping edge 17 which may be of the diamond point form as illustrated in Figs. 2 and 3, or of the forms illustrated in Figs. 5 to 8, inclusive. The diamond point illustrated in Figs. 2 and 3 would be especially adaptable for use wherein the incrustation formed within the interior of the boiler was very hard and brittle.

The end of the head 6 is provided with a transversely extending portion 18 the edge 19 of which may be engaged by the edge 20 of the chipping tool 7 to provide a stop therefor to limit the rotation of the tool 7 on the pin 8.

When the tool is in operation, each impact of the chipping tool 7 is accompanied with a corresponding rebound thereof which is transmitted back to the piston 12. Between the hitting of the piston 4 and the rebound of the chipping tool 7, the piston 12 is caused to reciprocate rapidly within the tube 9. For this reason it is necessary that the head 6 be of heavy construction so that the rebound of the chipping tool 7 will be transmitted to the piston 12 as described, and not to the head 6, as a head 6 of light construction would oscillate up and down so violently as to make the same difficult to manipulate. The pin 8 has a head 21 which fits in a recess 22 formed in the head 6. The pin 8 passes through a bore 23 formed in the head 6 and when the chipping tool 7 is mounted in position on the pin 8, the pin 8 is removably retained in position by means of a flat spring 24 which is pivotally mounted on a screw 25 screw threaded within the head 6 so that the spring 24 may be rotated to engage the head 21 and retain the pin 8 in position.

Means are provided for cooling the pin 8 during the operation of the tool as the continuous oscillation of the chipping tool 7 upon the pin 8 generates considerable heat. The exhaust air from the pneumatic cylinder 1 is employed for this purpose and is admitted into a cylinder 26 secured to the pneumatic cylinder 1 by any suitable means, such as clamp 27, and to which cylinder 26 a conduit or pipe 28 is secured. The pipe 28 is at its opposite end connected within the bore 29 formed in the head 6. The forward end of the bore 29 is of reduced diameter

as illustrated at 30 and is so positioned as to direct this exhaust air directly against the pin 8.

In order to permit easy manipulation of this pneumatic chipping device within a boiler, tongs 31 are provided which are adapted to be fitted within bores 32 formed in the head 6 as is illustrated in Figs. 4 and 9.

It will be obvious from the foregoing that I have provided a boiler chipping device which is of heavy construction, and which, due to the curved formation of the piston thereof, may be easily maintained against the surface to be chipped. This curved formation of the piston enables the entire device to be flat against the curved inner wall of the boiler and easily maintained in position so that the chipping tool which is operated by the device may be held in proper position to perform its functions. On the lower surface of the boiler, the greater portion of the incrustations are formed. Due to the heavy construction and curvature of the piston rod and the boiler chipping device, the same will be to a great extent maintained against this lower surface by gravity and may be easily maintained in the proper chipping position without the exertion of a great deal of energy by the operator of the same. The curvature of the pipe 9 and piston 12 enables the boiler chipping device to lie in a correct position within the boiler.

Referring now particularly to Figs. 5 and 6, the special form of chipping tool 7' shown therein, comprises a short chipping head 33 having a sharp edge 34. This particular type of chipping tool is particularly useful in removing incrustations that are in the form of cakes and are relatively hard where the same may be chipped from the shell of the boiler in relatively large portions.

The chipping tool 7'', illustrated in Figs. 7 and 8, comprises a chipping head 33' which has a more or less curved edge 34' and this special chipping tool 7'' is for the purpose of removing relatively soft incrustations formed upon the interior shell of boilers. The chipping tools 7, 7' and 7'' are interchangeable by means of removing the pin 8 and their use depends upon the condition of incrustation encountered upon the shell of the boiler.

Having fully described a preferred embodiment of this invention, it is to be understood that it is not intended that the same should be limited to the exact details of construction herein set forth, but may, obviously, be varied without departing from the spirit of the invention as set forth in the appended claims.

I claim:

1. In a device of the class described, the

- combination of a weighted head having a recess formed therein, a chipping tool pivotally mounted in the recess, a curved piston mounted at one end in a bore formed in the head in position to engage and actuate the tool, a curved tube secured to the head at one end and enclosing the curved piston, and means secured to the other end of the curved tube for actuating the piston.
2. In a device of the class described, the combination of a weighted head, a chipping tool removably and pivotally mounted within a recess formed in the head, a piston

rod curved to proximate the interior curvature of a boiler, the piston being mounted at one end in a bore formed in the head to reciprocate the chipping tool, means for limiting the pivotal movement of the chipping tool, a curved tube secured at one end to the head and housing the curved piston, and means secured to the other end of the curved tube for actuating the piston.

Signed at Famoso, California, this 27 day of June 1925.

FOSTER DOCKSTADER.
